UNITED STATES PATENT OFFICE.

HALLIE L. WRIGHT, OF WASHINGTON, DISTRICT OF COLUMBIA.

DESIGN FOR A SPOON.

SPECIFICATION forming part of Design No. 21,737, dated July 26, 1892.

Application filed July 2, 1892. Serial No. 438,828. Term of patent 3½ years.

To all whom it may concern:

Be it known that I, HALLIE L. WRIGHT, a citizen of the United States, residing at the city of Washington, in the District of Columbia, have invented and produced a new and original Design for Spoons, of which the following is a specification, reference being had to the accompanying drawing, forming part thereof.

10 The leading features of my design consist of a spoon having the shape and ornamentation hereinafter shown and described.

Upon the bowl of the spoon is displayed the portrait of Benjamin Harrison, surrounded 15 with a laurel wreath. Underneath said portrait is the representation of a log cabin. The main stem of the handle of the spoon consists

of a bundle of rods forming fasces, around which is entwined a ribbon adorned with stars. Above the fasces, emblemizing the union of the States and continuing up to the end of the bowl, is represented the United States flag. The extreme lower end of the handle below the base of the fasces consists of a representation of a hat of the bell-crown shape.

What I claim is—

The design for a spoon, as herein described and illustrated.

HALLIE L. WRIGHT.
